UNITED STATES PATENT OFFICE.

JOHN BRIGGS, OF SAN FRANCISCO, CALIFORNIA, ASSIGNOR OF ONE-THIRD TO GEORGE C. BORNEMANN AND ONE-THIRD TO RUSSELL BERKENKAMP, BOTH OF SAN FRANCISCO, CALIFORNIA.

MULTIPLE-DISK PHONOGRAPH.

1,395,035.

Specification of Letters Patent. Patented Oct. 25, 1921.

Application filed December 30, 1918. Serial No. 268,883.

To all whom it may concern:

Be it known that I, JOHN BRIGGS, a citizen of the United States, residing at San Francisco, in the county of San Francisco and 5 State of California, have invented new and useful Improvements in Multiple-Disk Phonographs, of which the following is a specification.

This invention relates to a phonograph 10 and particularly pertains to a machine of the multiple disk type.

It is the principal object of this invention to provide a phonograph adapted to automatically operate to successively play a 15 series of phonographic records; to repeatedly play any one of said records, both operations being automatic and produced by mechanism which may be actuated to discontinue the playing operation at an interval of time between the playing of the records or during the playing of the records.

The present invention contemplates the use of a multiple disk carriage, adapted to be motor driven and to successively present 25 records in operating relation to a driving mechanism and into register with a reproducer and its tone arm, said records and the tone arm being automatically controlled by a series of electric push buttons.

30 The invention is illustrated by way of example in the accompanying drawings, in which—

Figure 1 is a view in plan, disclosing the carriage equipped with phonographic records and further illustrating the relation of 35 the reproducer mechanism thereto.

Fig. 2 is a view in vertical section and elevation, as seen on the line 2—2 of Fig. 1, disclosing the complete operating mechanism, as well as a wiring diagram of the 40 electric circuits.

Fig. 3 is a view in vertical section on the line 3—3 of Fig. 1, disclosing the relation of the driving mechanism to the disk carriage.

Referring more particularly to the drawings, 10 indicates a suitable cabinet, preferably formed of wood and in which the phonograph mechanism is disposed. This 50 cabinet may be of any suitable design and is shown in Fig. 2 as having cross members 11 and 12, which members form the support for the electrical and mechanical mechanism. Mounted upon the member 11 are 55 bearings 13, adapted to support a carriage

axle 14 in a horizontal plane and for free rotation. Disposed between these bearings and mounted upon the axle, is a disk carriage 15. This carriage is in reality a wheel having spokes or central webbing, around 60 the circumference of which a rim 16 is formed. Recesses 17 are cut in the rim at intervals and receive disk driving wheels 18. These wheels stand tangentially to the circumference of the carriage and are mounted 65 upon pins 19, extending radially through bearings in the carriage rim. The wheels 18 are intended to be frictionally driven and are secured upon the pin 19 to drive it and a phonographic disk 20 which is detachably 70 secured to the end of the pin by means of a fastening member 21. This member extends through slots formed on the outer end of pin 19 and performs an additional function in connection with the electrical apparatus of the mechanism, as will be herein-after set forth.

The phonographic disks are disposed in equal spaced relation to each other around the circumference of the wheel and are in 80 the present instance shown to be seven in number. It will be understood that the dimensions of the disks and the diameter of the carriage will determine the number of disks which may be used at any one time. 85 The rim 16 on the wheel is in constant frictional engagement with a friction driving disk 22, more particularly shown in Fig. 3 of the drawing. This disk is mounted upon an oscillating shaft 23, which is disposed 90 in fixed radial relation to the carriage and may swing laterally thereof, as influenced by a spring 24. The shaft, however, swings in unison with suitable gearing shown in Fig. 3 and inclosed within the gear box 25, 95 indicated in Fig. 2. This gearing and its box are free to swing upon pivot arms 26, which are appropriately pivoted to the floor 12 and permit the entire structure to move, as previously specified. The shaft 23 is 100 driven from a drive shaft 27, through suitable gearing 28, interposed between the end of the shaft 27 and the vertical shaft 23. It will be understood that any type of gearing might be used to permit a small movement of the driving structure to insure constant frictional engagement of the disk 23 with the driving wheel 17 or the rim 16 of the carriage.

Mounted within the gear box 25 is also a 110

governor mechanism 29, by which uniform speed of rotation is insured. In the present instance, the drive shaft 27 is fitted with a pulley 30 and a belt 31. This belt also 5 embraces a small driving pulley 32 mounted upon the armature shaft of the driving motor 33. The motor is supported upon the floor 12. The top floor 12' of the cabinet is opened, as shown in Fig. 1, and provides 10 a support for a tone arm 34, which may swing in a plane tangent to the rim of the carriage 15 and thus pass across the plane face of phonographic disks. During the playing operation, the swinging movement 15 of the tone arm will be produced by the tone grooves upon the record disk as they are traversed by the reproducing needle 35. When the phonograph is in non-playing condition, the tone arm is lifted and swung 20 out of its contact with the record disk by means of a tone arm shifting lever 36 and to a position against a stop pin 5. This lever may be swung vertically and is carried upon a pivot pin 37. The pivot pin in turn is 25 fixed within a bracket 38 which is mounted upon the floor 12'. The lever 36 is normally supported in its uppermost position by means of an operating lever 39, which is carried by the pin 37 and has a forwardly 30 extending portion upon which a supporting pin 40 normally rests. The supporting pin 40 extends outwardly from the side of the lever 36 and overhangs this extension of the operating lever. 35 An examination of Fig. 2 will show that when this operating lever has been swung away from the pin 40, the lever 36 may swing downwardly under the influence of the weight of the tone arm 34 and as resisted by the action of a bellows 41, which 40 is connected with the end of the lever 36 by means of a link 42.

Fastened upon the extension end of the operating lever 39 is a link 43 which pivotally depends therefrom and is formed with 45 a slotted opening near its lower end, within which a pin 44 is seated. This pin is carried by an oscillating lever 45 mounted upon a bracket 46 within the phonograph cabinet. The bracket carries a pivot shaft 47, by which the arm 45 is supported. Fixed 50 upon this same pin is a catch member 48, the hooked end of which is disposed in the path of travel of carriage stop pins 48' and 55 will be engaged thereby when the oscillating arm 45 is swung downwardly by the action of the operating member 39 and the movement of the link 43. The operating lever 39 is initially actuated by a lever 49 60 pivoted to the floor 12' and connected therewith by a shackle link 50. The opposite end of this lever is fastened by a draw rod 51 to the plunger 52 of a solenoid 53. The electrical connections for this solenoid will 65 be hereinafter described.

Coöperating with the lever 39 is a bell crank 54 which is provided to seat beneath the end of the lever after it has been operated to release the tone arm and thus to hold it during the playing operation. The 70 operating lever is held against this bell crank by a tension spring 55. The free end of the bell crank 54 is fitted with a push rod 56, connected with a releasing magnet 57. This magnet also actuates a swinging 75 lever 58, mounted upon a pivot standard 59. The outer end of this swinging lever is intended to normally support a knife switch blade 60 which is pivoted at 61, and under the influence of spring 62, may be brought 80 to register with the contact finger 64, thus completing an electric circuit. The supporting end of the swinging lever 58 is normally locked beneath the switch blade 60 by means of a catch 65. This catch is in 85 reality the armature of a magnet 66 and may be swung out of its obstructing position beneath the lever 58 by energization of this magnet. A spring 67 normally holds it in its locking position. An auxiliary 90 switch is provided for a purpose to be specified and consists of a switch blade 68 formed in the shape of a bell crank. One leg of this crank is adapted to stand in the path of travel of the carriage stop pins 48 and 95 the other leg is designed to be brought into contact with a finger 69 by which the circuit will be completed. A spring 68' normally holds the switch blade and the finger out of engagement and is only overcome by the 100 pressure of the pin 48, thereby completing a circuit through solenoid 53.

In order to automatically stop the phonograph at the end of the playing operation, a pair of spaced contact fingers 70 and 71 are 105 provided. These fingers are carried by the reproducer of the phonograph or the tone arm, as convenience may dictate. At least one of these fingers is flexible so that the two may be brought together to complete 110 a circuit by which the operation of the motor will be discontinued. These fingers will move into the path of travel of the disk fastening pin 21 as the tone arm swings inwardly and the swinging action of this pin 115 will draw them together, thus producing the operation desired.

In operation, the numeral 72 indicates a source of electric supply. This supply is normally represented by the current delivered for household use, which is constantly 110 volts. The lead wire 73 is fitted with a switch 74. This switch in turn is connected by a suitable conductor with a wire 75 leading to one pole of the solenoid 125 coil 53 and wire 76, primarily connected with one pole of a transformer 77. This wire also has an extension 78 connecting with one of the brushes of the operating motor 33. The other brush is fitted with a 130

conductor 80 leading to a binding post 81 which is electrically connected with the switch blade 60. The current then passes through the switch blade and the finger 64 5 to a conductor 82, thereafter connecting with a wire 83, which represents the opposite lead wire of the source of supply. The lead wire 83 also connects with the other incoming pole of the transformer 77 by 10 means of an extension wire 84.

Briefly reviewing this wiring arrangement, it will be seen that a transformer circuit is established through the wires 76, 83 and 84 and a motor circuit is established 15 through the wires 76, 78, 80, the switch blade 60 and its finger 64 and return wires 82 and 83. These circuits will represent the potential of the feed wires. A current passing through the high voltage wire 75 will enter 20 the coil of the solenoid 53 and will lead through a conductor 85. This conductor is connected with the contact member of a repeating switch 86, through the blade of which the current passes to a return conductor 25 87. The conductor 87 is directly connected with the wire 84, which is a continuation of the feed wire 83, thus completing a high voltage circuit for the solenoid 53. The conductor 85 also communicates 30 with a switch wire 88 fastened to one pole of the switch 68, through which switch the current will pass and thereafter flow along a return conductor 89 in communication with the wire 80. The remaining circuits 35 are low voltage circuits and in the present instance represent approximately twenty-seven volts. Low voltage wire 90 leaves one of the outgoing poles of the transformer and passes to one end of the magnet 40 coil 66, the other end of this coil being connected with a wire 91. The wire 91 leads to an operating switch 92' and conducts a current therethrough to a wire 92 which returns and is fastened to the opposite 45 outgoing pole of the transformer. Connected to the wire 90 is also a wire 93 which is in communication with one end of the coil of the magnet 57. The opposite end of this coil is fitted with a conductor 50 94 passing to one pole of a stop switch 95, the opposite pole of this switch being provided with a conductor 96 leading to the contact finger 71 upon the reproducer. A current may be completed through the contact finger 71 and the contact finger 70 and may then pass along a wire 97 to unite with the wire 94 leading to the starting switch. The wire 96 is also fastened to the wire 92.

In starting the machine, switch 92' is 55 closed. This completes the circuit between the conductors 91 and 92; the circuit passing along the wire 92 from the transformer passes through the switch 92', then along the wire 91 and through the magnet 67, thereafter returning to the transformer along 60

the conductor 90. This action will energize the magnet and cause it to influence the catch 65, thus swinging it from beneath the switch blade 60. Due to gravity and the spring 62, the blade will fall and make contact with the finger 64. This contact will close the main motor circuit and complete this main circuit through the motor and the switch, as previously described. When this has taken place, the driving disk 32 will 70 be placed in continuous operation and will act to rotate the carriage as it comes into frictional engagement with the side of the carriage rim. As the carriage rotates in the direction of arrow *a*, as indicated in Fig. 2, 80 the pin 48 will move into contact with the switch member 68, thus completing the circuit through this member and the switch finger 69. High voltage current will then pass from the source of supply through the conductor 75 to the solenoid 53, then passing along the conductor 85 to the conductor 88, through the switch blade 68 and the finger 69 to the conductor 80 and thence returning 85 as described, to the source of supply. 90 This action will, of course, energize the coil of the solenoid 53 and draw its core downwardly. This will swing the lever 49 in the direction of arrow *b* and act to swing the operating lever 39 in the direction of arrow *c*. 95 The forward extension of the actuating lever 39 will, of course, swing downwardly and from its supporting position beneath the pin 40. This will leave the tone arm lever 36 unsupported and as it swings downwardly in the direction of arrow *b*, will lower the needle of the tone arm onto the record. The lowering of the tone arm will, of course, be retarded by the cushioning action of the bellows 41. Simultaneous with this operation, as instigated by the energization of the solenoid 53, the link 43 will press downwardly upon the oscillating lever 45 and swing the catch member 48 into the path of travel of the 100 lock pins 48', thus temporarily locking the carriage against movement. 105

In the event that it is desired to repeat the selection played upon the record, the switch 86 is closed. It will be noted that the 115 plunger of this switch is provided with an arm 86' which may also be brought to engage the knife of the switch 92. When the switch 86 is closed, the switch 92 will, of course, be closed and a circuit will be established through conductor 92 and the switch 92'. The finger 86' of the switch 86 will tend to hold the switch 92' in its closed position. At the same time a high voltage circuit will be established by the switch 86. 125 This circuit will pass from the source of supply along the wires 83 and 84 to the switch 86, returning on the wire 85 to the coil of solenoid 53, thence through the conductor 75 and 73, to the source of supply. Thus, upon 130

closing the switch 86, the solenoid 53 will be actuated to permit the tone arm to again rest upon the record and repeat the selection, it having been previously restored to 5 its original position by the action of the pin 21 fastening the record as it closes the circuit through the fingers 70 and 71. This causes conductor 96 to be connected with the conductor 92 along which the current passes 10 to one pole of the transformer, the conductor 97 being connected with the conductor 94 leading to the solenoid 57. The current then passes through conductor 93 and returns to the transformer along conductor 90. This 15 action releases the operating arm 39 from the supporting member 54 and allows the spring 55 to thrust the tone arm lever 36 upwardly and thereby swings the tone arm on its pivot and away from the disk. If the 20 machine is to be stopped while in the course of playing a record, the switch 95 is closed. This switch will complete a circuit from the transformer along the wire 92, through wire 96 to the switch 95 and therethrough, returning 25 along wire 94 to the coil of the solenoid 57 and then passing to the transformer along wires 93 and 90, as previously described, thus allowing the arm 36 to be thrown upwardly before the playing operation is complete. 30 If it is desired to successively play the record rod 100 may be rotated. The lower end of this rod is fitted with a crank-extension which engages the upper end of the locking member 65 and when rotated will swing the 35 catch 65 outwardly from its supporting position beneath the end of lever 58 and thus will permit the switch-blade 60 to fall.

It will thus be seen that by the arrangement here disclosed, an automatically operated phonograph is provided for successively playing a series of records or repeatedly playing a single record.

Reference being had to Fig. 1, it will be noted that the fastening members 21 are 45 formed with two fingers integrally connected and preferably made from spring steel. These fingers are adapted to yieldably grip the opposite sides of pins 19 as they pass along the grooves in the sides of these pins. 50 By this arrangement the fingers not only provide an adjustable fastener for disks of various thickness but provide an adjustable member for making contact between the two contact fingers carried by the reproducing mechanism. In this manner the position of 55 the fasteners 21 may be made to bear a direct relation to the record grooves, thus causing the discontinuance of the playing operation when the end of the record groove has 60 been reached.

Having thus described my invention, what I claim and desire to secure by Letters Patent is—

1. A phonograph comprising a rotary carriage, a plurality of individually rotatable

turn-tables supported upon such carriage and adapted to receive record disks and to hold said disks tangentially in relation to the axis of such carriage, a tone arm disposed at a point along the path of travel of 70 said record, means for rotating the carriage to dispose a record disk in playing relation to the tone-arm, and driving means engaging the turn table to rotate the same when the disk is disposed in said playing position. 75

2. In a phonograph, a revoluble carriage, disk receiving means mounted around the periphery of said carriage and tangential to the rotating axis thereof, a reproducing mechanism, means for successively and automatically disposing the disks carried by the carriage in playing relation to said mechanism and means for individually rotating the disk disposed in playing relation to said mechanism. 80

3. In a phonograph, a revoluble carriage, disk receiving means mounted around the circumference of said carriage and tangential to the rotating axis thereof, a reproducing mechanism, means for successively and automatically disposing the disks carried by the carriage in playing relation to said mechanism, means for individually rotating the disk disposed in playing relation to said mechanism, and optionally controlled means 90 for maintaining one of the disks in playing position, whereby it may be repeatedly played by automatic operation of the mechanism. 95

4. A phonograph comprising a vertically 100 revoluble carriage, a plurality of means carried thereby and upon which disk records are disposed in tangential relation to the rotating axis of the carriage for individual rotation, a relatively fixed reproducing mechanism, driving means for the phonograph and means for automatically and successively bringing the record disks into playing relation to the reproducing mechanism and for driving the disk when so disposed. 105

5. A phonograph comprising a vertically 110 revoluble carriage, tangentially arranged turn-tables disposed thereon and mounted for individual rotation, a relatively stationary reproducing mechanism driving means 115 for the phonograph and a driving member operated thereby for producing intermittent rotation of the carriage and rotation of one of the turn-tables when it is in playing relation to said reproducing mechanism. 120

6. A phonograph comprising a revoluble carriage, means disposed around the circumference thereof and upon which disk records are disposed for individual rotation, a reproducing mechanism, driving means for the 125 phonograph, means for automatically and successively bringing one of the record disks into register with the reproducing mechanism and thereafter disposing said mechanism in playing relation to the disk, means 130

for driving said disk when so disposed, and means for optionally interrupting the playing operation and restoring the reproducing mechanism to its non-playing position when 5 desired.

7. In a phonograph a vertically disposed and freely revoluble carriage, independently revoluble turn-tables carried by the carriage, and a single driving member for intermittently operating the carriage and successively operating the turn-tables.

8. In a phonograph, a freely revoluble carrier, a plurality of carrying spindles mounted around the circumference of said 15 carrier to receive disk records, a single driving member adapted to cause rotation of the carrier and to produce individual rotation of the spindles as the carriage is revolved and automatically operating means for holding 20 the carriage with the driving means in operating relation to one of the spindles, whereby a desired period of rotation of the spindle may be effected, and means for automatically disposing a reproducing mechanism 25 in playing relation with the record disk when the carriage is so locked, means for automatically raising the reproducer when the record has been played, and simultaneously releasing the carriage for further 30 rotation, and means for interrupting the playing operation and causing the release of the carriage when desired.

9. In an automatic phonograph, a tone arm adapted to swing radially from the center and across the surface of a disk record, 35 means normally holding said tone arm in a non-playing position, means for releasing said tone arm at the beginning of a playing operation, cushioning means against the 40 action of the reproducing needle when the tone arm is lowered onto the record, and means for automatically locking the tone arm control mechanism at the completion of said operation.

45 10. In an automatic phonograph, a tone arm adapted to swing radially from the center and across the surface of a disk record, means normally holding said tone arm in a non-playing position, means for releasing said tone arm at the beginning of a playing operation, cushioning means against the 50 action of the reproducing needle when the tone arm is lowered onto the record, means for automatically locking the tone arm control mechanism at the completion of said lowering operation, and means for automatically releasing the tone arm mechanism and causing it to restore the arm to a non-playing 55 position at the completion of its playing 60 movement.

11. In a phonograph, a reproducing mechanism adapted to move across the face of a disk record, means normally holding said reproducer in a non-playing position, 65 means for releasing said reproducer for

playing and means for optionally causing the reproducing mechanism to be restored to its non-playing position at any time during the playing operation.

12. In an automatic phonograph, a freely 70 revoluble carriage wheel, a plurality of spindles capable of independent rotation and extending radially through the rim of said wheel, friction wheels upon each of said spindles for producing rotation thereof 75 and a friction driving member resting against the side of said carriage wheel and adapted to successively encounter the driving wheels of the spindles as it rotates the wheel.

13. In an automatic phonograph, a freely 80 revoluble carriage wheel, a plurality of spindles capable of independent rotation and extending radially through the rim of said wheel, friction wheels upon each of 85 said spindles for producing rotation thereof and a friction driving member resting against the side of said carriage wheel and adapted to successively encounter the driving wheels of the spindles as it rotates the 90 wheel, an electric motor for operating said driving wheel, an electric switch within the mechanism, an electric circuit including the motor and said switch and an electric control means for permitting the closing of said 95 switch.

14. In an automatic phonograph, a freely 100 revoluble carriage wheel, a plurality of spindles capable of independent rotation and extending radially through the rim of said wheel, friction wheels upon each of said spindles for producing rotation thereof, a 105 friction driving member resting against the side of said carriage wheel and adapted to successively encounter the driving wheels of the spindles as it rotates the wheel, an electric motor for operating said driving wheel, an electric switch within the mechanism, an electric circuit including the motor and said 110 switch and an electric control means for permitting the closing of said switch, a reproducing mechanism, means for lowering said mechanism onto the record disk carried by one of the spindles and electric operating means for effecting said lowering operation simultaneous with the closure of the 115 motor switch.

15. In an automatic phonograph, a freely 120 revoluble carriage wheel, a plurality of spindles capable of independent rotation and extending radially through the rim of said wheel, friction wheels upon each of said spindles for producing rotation thereof, a 125 friction driving member resting against the side of said carriage wheel and adapted to successively encounter the driving wheels of the spindles as it rotates the wheel, an electric motor for operating said driving wheel, an electric switch within the mechanism, an electric circuit including the motor and said 130

switch, an electric control means for permitting the closing of said switch, a reproducing mechanism, means for lowering said mechanism onto the record disk carried by 5 one of the spindles, electric operating means for effecting said lowering operation simultaneous with the closure of the motor switch, means for automatically locking said mechanism in its inoperative position, and electrically actuated means for releasing said lock mechanism at the conclusion of the 10 playing operation.

16. In an automatic phonograph, a carriage wheel freely rotatable upon an axle, 15 an annular rim formed around the wheel and providing a driving surface, a plurality of disk spindles mounted through the rim and freely rotatable, and friction driving disks carried by each of the spindles and 20 standing with their circumferential surfaces substantially flush with the driving side of the rim.

17. In an automatic phonograph, a carriage wheel freely rotatable upon an axle, an 25 annular rim formed around the wheel and providing a driving surface along its side, a plurality of disk spindles mounted through the rim and freely rotatable, friction driving disks carried by each of the 30 spindles and standing with their circumferential surfaces flush with the driving side of the rim, and a friction driving disk adapted to normally engage the side of the carriage rim and to successively encounter the 35 driving disks upon the spindles as rotation of the carriage is produced.

18. In a phonograph, a driving spindle adapted to be vertically disposed and to 40 horizontally support a phonographic disk, a tone arm carrying a reproducer mounted to swing horizontally across the face of said disk, motor driven means for driving the spindle, a main motor circuit, a switch controlling the same, locking means for normally holding the switch in its open position, an auxiliary electrical circuit for the 45 lock means, an operating switch controlling said auxiliary circuit and whereby the closing of said operating switch will act to release the main switch and allow it to automatically close the motor circuit.

19. In a phonograph, a driving spindle adapted to be vertically disposed and to horizontally support a phonographic disk, a tone 55 arm carrying a reproducer mounted to swing horizontally across the face of said disk, motor driven means for driving the spindle, a switch for controlling the same, a motor circuit including the motor and said switch, 60 lock means normally holding the switch in its open position, an auxiliary circuit, an operating switch included in said auxiliary circuit, means whereby the closing of said operating switch will act to release the lock 65 means and the main switch and allow it to

automatically close the motor circuit, a secondary main circuit, and operating means adapted to be actuated thereby upon the closing of the motor switch, whereby the reproducing mechanism may be lowered onto the 70 disk to be played.

20. In a phonograph, a driving spindle adapted to be vertically disposed and to horizontally support a phonographic disk, a tone arm carrying a reproducer mounted to swing horizontally across the face of said disk, motor driven means for driving the spindle, a main motor circuit, a switch controlling the same and normally held in its open position, an auxiliary circuit, an operating switch controlling said auxiliary circuit, means whereby the closing of said operating switch will act to release the main switch and allow it to automatically close the motor circuit, a secondary main circuit and 80 tone arm operating means adapted to be actuated thereby upon the closing of the motor switch, whereby the reproducing mechanism may be lowered onto the disk to be played, automatically operating means 85 for locking said tone arm mechanism during the playing operation, and electric means for releasing said locking means at the conclusion of the playing operation.

21. In an automatic phonograph, a tone 90 arm adapted to swing across the playing surface of a disk record, a freely pivoted supporting arm extending beneath said tone arm and normally holding it in a non-playing position, a secondary arm normally holding 95 said supporting lever as described, and electric means for moving said secondary arm from its supporting position and thereafter causing the supporting arm to lower the tone arm to its playing position.

22. In an automatic phonograph, a tone arm adapted to swing across the playing surface of a disk record, a freely pivoted supporting arm extending beneath said tone arm and normally holding it in a non-playing 100 position, a secondary arm normally holding said supporting lever as described, electric means for moving said secondary arm from its supporting position and thereafter causing the supporting arm to lower the tone arm to its playing position and a bellows connected with said supporting arm for cushioning the downward movement of the tone arm and its reproducer.

23. In an automatic phonograph, a tone 110 arm adapted to swing across the playing surface of a disk record, a freely pivoted supporting arm extending beneath said tone arm and normally holding it in a non-playing position, a secondary arm normally holding 115 said supporting lever as described, electric means for moving said secondary arm from its supporting position and thereafter causing the supporting arm to lower the tone arm to its playing position, and a bellows connected with said supporting arm for cushioning the downward movement of the tone arm and its reproducer.

- automatic means for locking said secondary arm in its non-supporting position.
24. In an automatic phonograph, a tone arm adapted to swing across the playing surface of a disk record, a freely pivoted supporting arm extending beneath said tone arm and normally holding it in a non-playing position, a secondary arm normally holding said supporting lever as described, electric means for moving said secondary arm from its supporting position and thereafter causing the supporting arm to lower the tone arm to its playing position, automatic means for locking said secondary arm in its non-supporting position, and electrically actuating means for releasing said secondary arm at the conclusion of the playing operation.
25. In a phonograph, a freely rotatable carriage wheel, a driving member adapted to frictionally engage the side of said wheel and produce its rotation, a plurality of disk spindles extending radially through the rim of the wheel for independent rotation, friction wheels, one of which is mounted upon each of said spindles and will successively encounter the driving disk as the carriage rotates, an electric motor for driving said disk, a master switch, a main circuit including said motor and said master switch, means for normally holding the master switch in its opened position, a secondary circuit, an electro-magnet in said circuit adapted to influence said holding means to allow the master switch to automatically close, a push button controlling said secondary circuit for indirectly closing the master switch and starting the operation of the driving disk.
26. In a phonograph, a freely rotatable carriage wheel, a driving member adapted to frictionally engage the side of said wheel and produce its rotation, a plurality of disk spindles extending radially through the rim of the wheel for independent rotation, friction wheels, one of which is mounted upon each of said spindles and will successively encounter the driving disk as the carriage rotates, an electric motor for driving said disk, a master switch, a main circuit including said motor and said master switch, means for normally holding the master switch in its opened position, a secondary circuit, an electro-magnet in said circuit adapted to influence said holding means to allow the master switch to automatically close, a push button controlling said secondary circuit for indirectly closing the master switch and starting the operation of the driving disk, means for automatically locking the friction disks of the spindles in register with said driving disk, and electric control means for causing the carriage to be successively advanced and locked to permit the successive playing of the records carried thereby.
27. In an automatic phonograph, a freely revoluble carriage disk, a plurality of disk spindles mounted around the circumference of said carriage, a driving member for successively rotating the carriage and driving said spindles, an electric motor for operating said driving member, a master switch controlling said motor, a magnet adapted to release the master switch from its normally open position, an electric circuit including said magnet, a switch for closing said circuit, a second magnet adapted to restore the master switch to its open position, a reproducing mechanism, means whereby the completion of the playing movement of said reproducing mechanism will cause said second magnet to be energized, means for normally holding the reproducing mechanism in a non-playing position, an electric magnet adapted to be actuated by the closing of the master switch and which permits the reproducer to move to a playing position, catch means operated by said magnet for locking the disk carriage against movement when the reproducer is in playing position, and a lock member positively holding the reproducer lifting mechanism against movement during the playing position and electrically operated to release the same when said playing operation has been completed.
28. An automatic phonograph, a freely revoluble carriage disk, a plurality of disk spindles mounted around the circumference of said carriage, a driving member for successively rotating the carriage and driving said spindles, an electric motor for operating said driving member, a master switch controlling said motor, a magnet adapted to release the master switch from its normally open position, an electric circuit including said magnet, a switch for closing said circuit, a second magnet adapted to restore the master switch to its open position, a reproducing mechanism, means whereby the completion of the playing movement of said reproducing mechanism will cause said second magnet to be energized, means for normally holding the reproducing mechanism in a non-playing position, an electric magnet adapted to be actuated by the closing of the master switch and which permits the reproducer to move to a playing position, catch means operated by said magnet for locking the disk carriage against movement when the reproducer is in playing position, and a lock member positively holding the reproducer lifting mechanism against movement during the playing position and electrically operated to release the same when said playing operation has been completed, and manually operated means for preventing the locking of the master switch

when elevated, whereby a single disk will be maintained in playing position and repeatedly played.

29. In a phonograph, a revoluble shaft, a record disk carried thereby, a reproducing mechanism adapted to pass over the surface of the disk, electric driving means for said shaft, an electric control switch carried by the mechanism, electrically operated means for discontinuing said driving means and an adjustable fastener for securing the disk in position upon the shaft and for closing the circuit through said electrical control apparatus at the completion of the playing operation and thereby discontinuing the same.

30. In a phonograph, a freely revoluble carriage, a plurality of independently revoluble turn tables supported by the carriage and a single driving member adapted to be continuously operated and to directly act to intermittently move the carriage and successively rotate the turn tables.

31. In a phonograph, a freely revoluble carriage, a plurality of independently revoluble turn tables supported by the carriage and a single driving member adapted to be continuously operated and to directly act to intermittently move the carriage and successively rotate the turn tables, and automatically operating means to hold the carriage against movement during the interval of rotation of the turn tables.

32. In a phonograph a turntable having a spindle, power driving means therefor, a tone arm and a pair of insulated members carried on the arm for closing a circuit to interrupt said driving means when said springs are brought together, and a member adjustably and removably disposed upon the turntable spindle for engagement with one of said fingers at the completion of the playing movement of the tone arm across the turntable, and thus bringing said members together and closing the circuit therethrough.

33. In a phonograph a vertically disposed and freely revoluble carriage, independently revoluble turntables carried by the carriage, a single driving means for intermittently operating the carriage and successively operating the turntables, and governor control means for said driving means.

34. In a phonograph a rotatable carriage; a plurality of disks rotatably and detachably mounted about the periphery of said carriage and tangentially thereof, a reproducing mechanism, means for successively and automatically disposing the disks carried by the carriage in playing relation to said mechanism, and for individually rotating the disk when disposed in playing relation to said mechanism.

35. In an automatic phonograph, a ro-

tatable wheel carrying a plurality of disk records mounted for individual rotation about the periphery of said wheel and tangentially of said periphery, a reproducing mechanism and lowering mechanism for connecting said reproducing mechanism with a disk record when disposed in receiving position therefor, a driving means located beneath the reproducing mechanism and adapted to rotate the wheel until a disk record is brought into alinement therewith, and then to transfer its driving force to rotate the disk, a solenoid for actuating the lowering mechanism, said lowering mechanism acting simultaneously with the initial rotation of the disk to be played, means for locking the wheel against further forward rotative movement, when a disk record has been brought into position for receiving the reproducing mechanism, and means for energizing the solenoid before the disk record has reached its receiving position.

36. In an automatic phonograph, a rotatable wheel carrying a plurality of disk records mounted for individual rotation about the periphery of said wheel and tangentially of said periphery, a reproducing mechanism and lowering mechanism for connecting said reproducing mechanism with a disk record when disposed in receiving position therefor, a driving means located beneath the reproducing mechanism and adapted to rotate the wheel until a disk record is brought into alinement therewith, and then to transfer its driving force to rotate the disk, a solenoid for actuating the lowering mechanism, said lowering mechanism acting simultaneously with the initial rotation of the disk to be played, means for locking the wheel against further forward rotative movement, when a disk record has been brought into position for receiving the reproducing mechanism, and means for energizing the solenoid at a predetermined period, before a disk record reaches its receiving position.

37. In an automatic phonograph, a rotatable wheel carrying a plurality of disk records mounted for individual rotation about the periphery of said wheel and tangentially of said periphery, a reproducing mechanism and lowering mechanism for connecting said reproducing mechanism with a disk record when disposed in receiving position therefor, a driving means located beneath the reproducing mechanism and adapted to rotate the wheel until a disk record is brought into alinement therewith, and then to transfer its driving force to rotate the disk, a solenoid for actuating the lowering mechanism, said lowering mechanism acting simultaneously with the initial rotation of the disk to be played, means for locking the wheel against further forward rotative movement,

when a disk record has been brought into position for receiving the reproducing mechanism, and means actuated by the rotating wheel to energize the solenoid at a predetermined period before a record disk reaches its receiving position.

38. In an automatic phonograph, a rotatable wheel carrying a plurality of disk records mounted for individual rotation about the periphery of said wheel and tangentially of said periphery, a reproducing mechanism and lowering mechanism for connecting said reproducing mechanism with a disk record, when disposed in receiving relation therefor, a driving means located beneath the reproducing mechanism adapted to rotate the wheel until a disk record is brought into alinement and then to transfer its driving force to rotate the disk, a laterally extending pin at a point forward of each disk, with respect to the rotation of the wheel, a latch element actuated simultaneously with the lowering mechanism and disposed to coöperate with said pins, so as to lock the wheel against further forward movement when a disk record is in receiving position, a solenoid for actuating said lowering mechanism and circuit therefor, and means actuated by the rotation of the wheel for closing said solenoid circuit previous to the disk record reaching its receiving position.

39. In an automatic phonograph, a rotatable wheel carrying a plurality of disk records mounted for individual rotation about the periphery of said wheel and tangentially of said periphery, a reproducing mechanism and lowering mechanism for connecting said

reproducing mechanism with a disk record, when disposed in receiving relation therefor, a driving means located beneath the reproducing mechanism adapted to rotate the wheel until a disk record is brought into alinement and then to transfer its driving force to rotate the disk, a laterally extending pin at a point forward of each disk, with respect to the rotation of the wheel, a latch element actuated simultaneously with the lowering mechanism and disposed to coöperate with said pins, so as to lock the wheel against further forward movement when a disk record is in receiving position, a solenoid for actuating said lowering mechanism and circuit therefor, and a bell crank lever adapted to close the solenoid circuit previous to the disk record reaching its receiving position, said bell crank lever being actuated by the rotation of the wheel.

40. In a phonograph a turntable, a fixed spindle disposed centrally of said table, and over which a phonograph disk may be mounted, a tone arm adapted to swing across the face of said turntable, electric driving means for the turntable control means carried on the tone arm for discontinuing said electric driving means, and means adapted to be adjustably fixed to the spindle of the turntable for actuating said control means.

In testimony whereof we have hereunto set our hands in the presence of two subscribing witnesses.

JOHN BRIGGS.
